UNITED STATES PATENT OFFICE.

HENRY A. OWEN, OF WHITINSVILLE, MASSACHUSETTS, ASSIGNOR, BY MESNE ASSIGNMENTS, TO DRAPER CORPORATION, OF HOPEDALE, MASSACHUSETTS, A CORPORATION OF MAINE.

WEFT-FEELER MECHANISM FOR LOOMS.

1,291,624.

Specification of Letters Patent. Patented Jan. 14, 1919.

Application filed June 26, 1916. Serial No. 105,794.

To all whom it may concern:

Be it known that I, HENRY A. OWEN, a citizen of the United States, residing at Whitinsville, in the county of Worcester, 5 State of Massachusetts, have invented a certain new and useful Improvement in Weft-Feeler Mechanisms for Looms, of which the following is a specification, reference being had therein to the accompanying drawings. 10 The invention is an improvement in side-slipping feeler-motions for looms, such for example as disclosed in Patent No. 1,127,086 granted February 2, 1915, upon my application. The improvement resides in the combination of a side-slipping feeler of the 15 type referred to and a cam as the particular element whereby the effect of the side-slip is made apparent and transmitted through the controller devices to the mechanism 20 which produces the change in the operation of the loom. I have found that the use of a cam or cam face in the relation stated operates to eliminate much of the shock and jar to which these motions are subject when 25 calling the change and by which their period of useful service was greatly curtailed, and that thereby the reliability and accuracy of side-slipping motions are enhanced and their durability greatly improved. 30 The invention may be embodied variously in practice. The drawings show illustrative embodiments thereof.

Figure 1 of the drawings shows in plan certain portions of a loom having applied thereto one of the said embodiments of the invention, the lay being rearward, and the shuttle-box front-plate and the front wall of the shuttle occupying the shuttle-box being partly broken away.

40 Fig. 2 is a view thereof mainly in end-elevation, with the lay-beam in vertical section.

Fig. 3 is a view of the same general character as Fig. 1, but showing the lay at front center and illustrating the action when the feeler slips upon the weft-carrier occupying the shuttle and the change is called.

45 Fig. 4, Sheet 2, is an end elevation corresponding with Fig. 3, but with the lay omitted, the shuttle being shown in vertical section.

50 Figs. 5 and 6 are respectively, a plan view and a side elevation showing a second illustrative embodiment.

Having reference to the drawings,—
55 Certain of the views show a portion of the lay-beam *a* of a loom, and the shuttle-box at one end thereof, namely at the side of the loom at which the feeler-mechanism is located. A shuttle, *b*, is shown occupying the said shuttle-box, behind the front plate *c* of the latter, and a bobbin, *d*, is shown within the said shuttle, with weft thereon. Fig. 1 shows a substantially full bobbin-load, *e*, of weft, while Figs. 3 and 4 60 show the residue, *e'*, of weft remaining at the stage of exhaustion at which the feeler-mechanism calls a change in the operation of the loom. In Figs. 1 and 3 the front-plate and the front wall of the shuttle-body are 65 represented with portions thereof broken away, so as to show the slot *c'* in the front-plate and the slot *b'* in the front wall of the shuttle-body, through which the feeler passes into the shuttle and into contact with the 70 wound supply of weft that is contained therein.

75 Certain of the views show a portion of the breast-beam *f* of the loom, a weft-fork slide *g*, and a weft-fork *h*. Fig. 1 shows 80 also a portion of a weft-hammer *i* having a hook *h* for engagement with the tail of the weft-fork. In addition, the views show a knocking-off lever *m*, pivoted at *n* upon the shipper-bracket *o*, and engaging with the 85 weft-fork slide so as to be operated thereby for the purpose of dislodging the shipper-handle *p* from the holding notch therefor at one end of the slot *r* in the said shipper-bracket.

90 Each of the illustrative embodiments of the invention includes a slipping feeler 1 which is mounted pivotally at 2 upon a carrier 3, the latter being a swinging feeler-carrier as in the patent aforesaid. The 95 feeler-carrier 3 is mounted pivotally at 4, Figs. 1 and 3, upon a rearwardly-projecting portion 5^a of a feeler-stand 5 mounted upon the breast-beam. The feeler-carrier is held in its normal rearward position by means of a contracting spiral spring 7, the latter having one end thereof engaged with an arm of the said carrier and the other end thereof engaged with a pin or stud 8 fixed to the base or stand of the weft-fork slide *g*. The 100 said normal rearward position of the feeler-carrier 3 is defined by means of a suitable fixed stop 9 upon the stand 5. The said 105

spring returns the feeler-carrier to such position after the carrier has been pushed forward therefrom by the pressure of the weft against the feeling portion of the feeler.

5 Referring now to Figs. 1 to 4:—

The normal position of the feeler 1 upon the feeler-carrier 3 is represented in Fig. 1, and the feeler is kept in this position through the action of a contracting spiral 10 spring 10 having one end thereof engaged with an arm 11 projecting laterally from the feeler and the other end thereof engaged with the feeler-carrier. The said spring acts by its tension with a tendency to hold an 15 arm 12 which is connected with the feeler pressed against a fixed stop 13 upon the feeler-carrier, and the said stop defines the said normal position.

The controller may vary in construction, 20 arrangement, etc. In this instance it is a transversely-extending rockshaft 14 turning on a horizontal axis which is provided with arms 14^a and 14^b at its outer and inner ends respectively. The said rockshaft is mounted 25 in bearings 15, 15, with which the feeler-stand 5 is furnished. The outer arm, 14^a, extends rearwardly and is located in convenient proximity to the slipping feeler so as to facilitate the actuation of the controller by means of the controller-actuating cam which is provided in connection with the said feeler and constitutes the essential part of the operating connection whereby the latter operates or causes the operation 30 of the controller. The inner arm, 14^b, of the controller is located in convenient working relations with devices which are instrumental in calling a change in the operation of the loom, in order that it may be combined operatively with the said devices for the effective control of the latter. Through 35 the action of a spring which is suitably combined with the controller, the controller is rocked into its normal position of rest, which 40 is defined by means of a stop-finger 19 fixed upon the controller-rockshaft and engaging with the surface of a portion of the loom framework. In such position of the rocking controller, the arms 14^a, 14^b, thereof occupy 45 relatively elevated positions which are shown 50 in Fig. 2. In the present instance the said spring is a torsional spiral spring 18 surrounding the rockshaft and having one end thereof engaged with one of the bearings 15 and the other end thereof engaged with the 55 hub of the stop-finger 19.

The arm 12, of the feeler has at its forward end a controller actuating cam 20, with a vertically inclined cam face. The 60 said arm 12 projects forwardly from the pivotal mounting 2 upon the feeler-carrier 3, and so long as the said arm is held against the stop 13 on the feeler-carrier 3 the cam 20 travels in a path which clears the arm 14^a of the controller as the feeler-carrier is

driven forward by the pressure of the shuttle-contents against the feeler 1. Thus, so long as the weft-carrier *d* in the shuttle has thereon sufficient weft to keep the feeler from slipping laterally, the controller-actuating cam 20 moves forward with the feeler-carrier 3 without engaging with the arm 14^a. This will be apparent from Fig. 1 of the drawings. When, however, the feeling end of the feeler 1 is caused to slip laterally by the pressure of the substantially emptied bobbin *d* thereagainst, the swinging movement of the feeler around its pivot 2 moves the arm 12 so as to carry the vertically inclined face of the cam 20 into position to engage with the rear end of the arm 14^a of the controller, and consequently as the feeler-carrier 3 moves forward the said cam acts against the rear extremity of the arm 14^a substantially as in Figs. 3 and 4, so as to depress the said arm and rock the controller so as to move downward the arm 14^b at the inner end of the controller-rockshaft. Through such rocking of the controller the devices for calling a change in the operation of the loom are brought into action and rendered effective to call the change.

The devices for calling a change in the operation of a loom may be variously constituted and arranged, and the nature of the change that is called may vary in different cases. Sometimes in practice feeler-mechanisms are employed to bring about automatic weft replenishment. Sometimes they are employed to effect stopping of a loom. Herein is shown an arm 21 like that which usually is mounted in connection with the ordinary transversely-extending controlling-rockshaft of replenishing instrumentalities, and a catch or dog 22 mounted pivotally at 23 upon the rearwardly-extending upper end of the said arm. The catch or dog 22 is formed at the rear of the pivot 23 with a tooth or shoulder 22^a, Fig. 2, for co-action with a striker 24 carried by weft-hammer *i*. The forwardly-projecting arm of the catch or dog is overweighted, so that normally the catch or dog occupies the substantially horizontal position in which it is shown in Fig. 2, with a stop-pin 22^b which projects laterally therefrom resting in contact with the top of arm 21 and with the tooth or shoulder 22^a elevated above the path of movement of the striker 24. To provide for control of the catch or dog 22 by means of the controller, the arm 14^b of the latter is furnished with a laterally projecting pin 14^c which extends over the engaging end of the said catch or dog. Normally, that is to say while the stop-finger 19 is in contact with the stop-surface on the loom framework, the arm 14^b and pin 14^c of the controller are relatively elevated to an extent permitting the engaging end of the catch or dog to

occupy the position shown in Fig. 2 with the shoulder or tooth 22^a clear of the path of the striker 24. Consequently, as the weft-hammer operates during the regular working 5 of the loom the striker misses the catch or dog.

So long as the shuttle contains sufficient weft *e* to prevent the feeler from turning 10 around its pivotal mounting 2 upon the feeler-carrier 3 when the beating-up movement of the lay carries the shuttle-contents against the feeling-tip of the feeler, the controller-actuating cam 20 travels forward at one side of the controller-arm 14^a, thereby 15 missing the latter, as the pressure of the weft-mass against the feeling-tip of the feeler advances the feeler-carrier. When, however, the progressive depletion of the weft-mass contained within the shuttle arrives 20 at such a stage that the pressure applied against the feeling-tip of the feeler 1 during the advance of the lay causes such tip to slide along the bobbin as in Fig. 3, the turning of the feeler around its pivot 2, which results 25 from the offset relation of its tip with reference to its support, swings the cam 20 into line with the arm 14^a. Consequently, the advance of the feeler-carrier 3 caused by the continued pressure against the feeler will 30 cause the inclined face of the cam to encounter the arm 14^a of the controller. Thus the controller is given a glancing blow as the inclined face of the cam rides along it, so that the controller is moved gradually with 35 out shock. The rocking of the controller by the feeler cam depresses the engaging end of the catch or dog 22 and thereby places its tooth or shoulder 22^a in the path of the striker 24. Thereupon, the advancing movement 40 of the weft-hammer and striker will cause the striker to engage with the said tooth or shoulder 22^a, so that the catch or dog and arm 21 will be moved forward and thereby through the parts with which the 45 said arm is connected the change in the operation of the loom will be called. As the lay moves rearward, and the feeler-carrier follows it, taking the controller-actuating cam rearward out of engagement with the 50 arm 14^a of the controller, the controller will rock back into its normal waiting position under the action of the spring 18, thereby freeing the catch or dog 22 from the control of the controller, and the said catch or dog 55 will swing into its normal horizontal position represented in Fig. 2.

The catch or dog 22 of the embodiment of the invention that has just been described occupies normally a position in which it is 60 clear of the path of the striker, and the controller-actuating cam 20 normally clears the arm 14^a of the controller, and is brought into engaging relations with the said arm to actuate the controller to place the catch or dog in the path of the striker only when 65

the feeler slips in the feeling action. Figs. 5 and 6 show a construction in which the mode of operation is more or less on the order of a reversal of that just described. In Figs. 5 and 6 the controller-actuating cam 70 20^a is constructed so as to enable it to raise the controller-arm 14^a by passing under the said arm and pressing the latter upward. Spring 18 is arranged to rock the controller 75 reversely and hold the stop-finger 19 pressed against the rear edge of the top of feeler-stand 5. The said controller-actuating cam 20^a occupies normally a relative position such that as the lay goes forward the cam 80 engages the arm 14^a when the feeler is held from slipping, and by raising the arm rocks the controller. In this embodiment the arm 14^b at the inner end of the controller-rock-shaft and the pin 14^c carried by the said arm 85 occupy a position in which the said pin is adjacent the rear side of an upwardly-extending arm 22^a of the catch or dog, the latter being here designated 22^b. The said catch or dog of this embodiment normally occupies a position in which its tooth or engaging 90 shoulder 22^a is in the path of the striker. The forward rocking of the controller by the action of the controller-actuating cam 20^a causes the pin 14^c to act forwardly against the rear edge of the upwardly-extending arm 95 22^a so as to swing the engaging end of the catch or dog upward and thereby raise the tooth or shoulder 22^a out of the path of the striker 24, so that the striker fails to engage therewith as it goes forward. In this manner the catch or dog is moved clear of the path of the striker at every feeling action so long as the feeler is prevented from slipping. When, however, the weft has been reduced 100 to a residue *e'* (substantially as is shown in Figs. 3 and 4) insufficient to hold the feeler from slipping at the time of the feeling action, the turning of the feeler upon its pivot 2 which is consequent upon the said slipping 105 carries the controller-actuating cam 20^a out of engaging relations with the arm 14^a of the controller, and as the feeler-carrier 3 is moved forward through the advance of the lay the said controller-actuating cam 20^a 110 clears or misses the arm 14^a, so that the controller is not rocked. Thereby the catch or dog is permitted to remain in its normal position, with its tooth or shoulder 22^a in the path of the striker, and the striker as it goes 115 forward engages with the said tooth or shoulder and as a result of the said engagement 120 operates the catch or dog and arm 21 to call the change in the operation of the loom.

What is claimed as the invention is—
125 A feeler mechanism for looms having, in combination, a feeler carrier movable forwardly and backwardly, a side-slipping feeler supported by said carrier and moving thereon when the weft is depleted, a cam having a vertically inclined face at the for- 130

ward end of said feeler, and a controller turning on a horizontal axis and adapted to transmit a call for a change in the operation of the loom, said controller having a rearwardly extending arm which is normally out of the path of said cam, but when the feeler slips sidewise the vertically inclined face of the cam is brought into register with the rear end of the controller arm, and then, as the feeler carrier advances, the inclined face

of the cam rides along the rear end of the controller arm thereby gradually turning the controller.

In testimony whereof I affix my signature in presence of two witnesses.

HENRY A. OWEN.
